A. H. HANEY,
COMBINED COSTUMER AND WARDROBE,
APPLICATION FILED SEPT. 29, 1917.

1,268,346.

Patented June 4, 1918.

UNITED STATES PATENT OFFICE.

ADAM H. HANEY, OF CHILLICOTHE, OHIO.

COMBINED COSTUMER AND WARDROBE.

1,268,346.

Specification of Letters Patent. Patented June 4, 1918.

Application filed September 29, 1917. Serial No. 194,003.

To all whom it may concern:

Be it known that I, ADAM H. HANEY, a citizen of the United States, residing at Chillicothe, in the county of Ross and State 5 of Ohio, have invented certain new and useful Improvements in Combined Costumers and Wardrobes, of which the following is a specification, reference being had to the accompanying drawings.

10 This invention relates to certain improvements in a combined costumer and wardrobe, and it is an object of the invention to provide a novel and improved device of this general character including a plurality of 15 separable members together with means whereby said members may be readily and conveniently assembled.

It is also an object of the invention to provide a novel and improved device of this 20 general character including a supporting standard or column comprising two sections and wherein one of said sections is capable of rotation independently of the second section and wherein said rotatable section is 25 provided with garment supporting means.

Furthermore it is an object of the invention to provide a novel and improved device of this general character including a standard or supporting member having a top or 30 crown piece rotatably engaged with the upper end portion of the standard or supporting member together with a curtain or curtains depending from the marginal portion of said top or crown piece.

35 The invention consists in the details of construction and in the combination and arrangement of the several parts of my improved costumer and wardrobe wherein certain important advantages are attained and 40 the device rendered simpler, less expensive and otherwise more convenient and advantageous for use, as will be hereinafter more fully set forth.

The novel features of my invention will 45 hereinafter be definitely claimed.

In order that my invention may be the better understood I will now proceed to describe the same with reference to the accompanying drawings wherein:

50 Figure 1 is a vertical sectional view illustrating a combined costumer and wardrobe constructed in accordance with an embodiment of my invention; and

Fig. 2 is a fragmentary view in bottom 55 plan illustrating a portion of the means

for maintaining the legs in assembled position.

As disclosed in the accompanying drawings S denotes a supporting member or standard comprising two sections 1 and 2 adapted to be longitudinally aligned when in assembled relation. The inner end portion of the lower section 1 is provided at its axial center with the longitudinally disposed elongated socket 3 adapted to snugly receive the cylindrical shank 4. An end portion of the shank 4 is threaded as indicated at 5 so that said shank may be detachably engaged with the end portion of the upper section 2 of the standard at substantially 60 the axial center thereof. The shank 4 affords means whereby the upper section 2 may be maintained in applied position relative to the section 1 and whereby said section 2 may be capable of rotation relative to the 65 section 1.

The outer or lower end portion of the section 1 of the standard or supporting member S is provided therethrough with the transversely disposed openings 6 herein disclosed as arranged in pairs with one pair of openings arranged at right angles to the second pair and with the openings of each pair in longitudinally spaced relation. An end portion of each of the openings 6 is enlarged as indicated at 7 and the enlargement 7 of each pair of openings are reversely disposed. The elongated screw members 8 are adapted to be disposed through the openings 6 with the heads 9 thereof snugly fitting within the enlarged portions 7 so that said screw members are held against rotation. Each of the screw members 8 is of such a length as to extend a predetermined distance beyond the faces of the section 1 90 of the standard or supporting member S and said extended portion is adapted to be engaged by a leg 10. The leg 10 is properly applied in operative position by rotating the same around the extended portion of the 95 screw member 8.

As herein embodied the legs 10 are four in number and when properly engaged with the screw members 8, the opposed legs have engaged therewith through the medium of 105 the thumb screws 11 the straps 12 which underlie the outer or lower end of the section 1 and secured to said lower end of the section 1 by the screw 14. The screw 14 contacts with both of the straps 12. It has been 110

found of advantage to position at the inner end of the socket 3 the metallic disk or wear plate 15 and with which the outer end of the shank 4 is adapted to contact. The section 5 2 has disposed therethrough the openings 16, preferably two in number spaced longitudinally of the member 2 and arranged at right angles one relative to the other. Disposed through each of the openings 16 is an 10 elongated shank 17 of a length to extend beyond opposite sides of the member 2 and said extended portions 18 are of screw formation so as to operatively engage the hook members 19 formed preferably of wood. 15 In applying the hook members 19 the same are rotated relative to the shank 17. By this means it will be at once understood that opposed hooks 19 are effectively maintained in applied position. 20 The upper or outer end of the section 2 of the standard or supporting member S is provided at its axial center with the longitudinally disposed socket 20 adapted to have seated therein an end portion of the elongated member or shank 21 of a length to extend beyond the end of the section 2. The extended portion of the member 21 is threaded as indicated at 22 and is adapted to be disposed through the axial center of the top 25 or crown member 23. Engaged with the threaded portion 22 of the elongated member 21 are the nuts 24 positioned at opposite sides of the top or crown member and in contact therewith. The nuts 24 serve to 30 effectively hold the top or crown member 23 and the elongated member 21 in assembled relation.

Depending from the top or crown member 23 are the hat hooks or hangers 25 and 40 also depending from the top or crown member 23 are the hooks 26 for supporting articles of wearing apparel.

Secured to the marginal portion of the top or crown member 23 through the medium 45 of the tacks 27 or the like are the curtains 28 of a length to substantially entirely surround the portion of the standard or supporting member S above the legs 10. In view of the foregoing it is to be noted that 50 my improved device may be readily assembled or taken apart and that convenient access may be had to the articles supported by the device either by rotation of the upper section 2 or by rotation of the top or crown member 23 and which rotary movement of the top or crown member 23 is afforded by the elongated member 21 seated within the

socket 20. It is also to be understood that when the several members of my improved device are separated the same can be conveniently carried in a trunk or suitcase. 60

From the foregoing description, it is thought to be obvious that a combined costumer and wardrobe constructed in accordance with my invention is particularly well adapted for use by reason of the convenience and facility with which it may be assembled and operated and it will also be obvious that my invention is susceptible of some change and modification without materially departing from the principles and spirit thereof and for this reason I do not wish to be understood as limiting myself to the precise arrangement and formation of the several parts herein shown in carrying out my invention in practice except as hereinafter claimed. 75

I claim:

1. A device of the character described comprising a supporting member, the lower 80 end portion of the supporting member being provided with angularly related openings disposed therethrough, headed shanks insertible through said openings and extending beyond the supporting member, the extended 85 portions of the shank being of screw formation, legs engageable with the extended portions of the shanks and straps detachably engaged with the legs and with the adjacent end of the supporting member, each of the 90 legs overlying a head of a second shank.

2. A device of the character described comprising a supporting member, the lower 95 end portion of the supporting member being provided with angularly related openings disposed therethrough, headed shanks insertible through said openings and extending beyond the supporting member, the extended portions of the shank being of screw formation, legs engageable with the extended portions 100 of the shanks, and straps detachably engaged with the legs and with the adjacent portion of the supporting member, said shanks being arranged in pairs, the shanks of each pair being reversely directed, each leg overlying the head of the shank extending in a direction opposite to the shank with which the leg is engaged. 105

In testimony whereof I hereunto affix my signature in the presence of two witnesses. 110

ADAM H. HANEY.

Witnesses:

FRANK P. HINTON,
EDWARD J. BROWN.
